William Rose, Philip Morris

Setters Patent

81⁶8^x

This Schedule referred to in these Setters Patent and making part of the same containing a description in the words of the said William Rose himself of his improvement in the Machine for hulling Corn-Seed & other grains.

To all whom these present shall come Be it known that I William Rose of Phillips in the County of Somerset and State of Maine have invented a new and useful improvement in hulling Corn-Seed rice or other grains and that the following is a full and exact description of the construction and operation of the said Machine as invented or improved by me.

A Cylindrical Cylinder is formed of wood, or other suitable materials of about two feet in diameter at the top and diminishing to about one foot in diameter at the bottom. This Cylinder is lined with strips of Sheet iron perforated through all the surface with holes punched from the outside to a strong cutting surface similar to that of a greater projecting axmills.

Within this Cylinder thus finished works a central Axle or screw secured in its vertical position by a projection of the axis at the bottom working in a Step formed to receive it at the bottom of the Hollow Cylinder. This Core is fashioned into a screw the projections of the Thread being covered with strips of perforated Sheet iron with the roughness projecting against those of the Cylinder. The axis of the core projects on top about from to which it is adjusted sufficiently to receive the means or gearing by which it is to be driven which may be applied at either end of the axis and which may be simply a lever slipping on the top and turned by a hand after the manner of a Corn Mill or by Steam water or any other power.

Sufficient Space is left between the core and the Cylinder to receive the substance to be hulled or rubbed and this Space is wider at the top than the bottom. To the bottom of this Machine is adjusted an apparatus for separating the seed or grain from the Chaff and consists of two discs the one below the upper one the finest and serving to con-

of the feed or grain completely cleaned from the hull on to a kind of shelf below which by the violent shaking of the whole and the interaction of which it falls from above a plough of feed to the action of a fan blowing directly into the mouth of the animal a large amount of feed is removed but is not destroyed. The fan removes the chaff and the hull and the plough carries off the hull or chaff and the plough carries the cleaned feed falling into a current of wind which sweeps it in a heap at the mouth ready for market.

I certify that the above is a correct specification
of my machine as wanted by me. I then caused to be signed this twenty second
day of April eighteen hundred and thirty four (1834) M
